UNITED STATES PATENT OFFICE.

LAURENT RUEL, OF MERRIMAC, ASSIGNOR TO WALTER M. BREWSTER, OF GEORGETOWN, MASSACHUSETTS.

MACHINE FOR MAKING FELT BOOTS, SHOES, &c.

SPECIFICATION forming part of Letters Patent No. 324,340, dated August 11, 1885.

Application filed May 12, 1884. (No model.)

To all whom it may concern:

Be it known that I, LAURENT RUEL, a subject of the Queen of Great Britain, residing at Merrimac, in the county of Essex and State 5 of Massachusetts, have invented a certain new and useful Improvement in Machines for Manufacturing Felt Boots, Shoes, or Stockings, of which the following is a description sufficiently full, clear, and exact to enable any 10 person skilled in the art or science to which said invention appertains to make and use the same, reference being had to the accompanying drawings, forming a part of this specification, in which—

15 Figure 1 is a side elevation of my improved machine; Fig. 2, an end elevation; Fig. 3, a top plan view; Fig. 4, an end elevation, the reverse of Fig. 2; and Fig. 5 a vertical transverse section taken on line *x* in Fig. 3.

20 Like letters of reference indicate corresponding parts in the different figures of the drawings.

My invention relates more especially to 25 means for holding and manipulating the former or cone on which the "sliver" or felting material is deposited in the manufacture of felt boots, shoes, or stockings; and it consists in a novel construction and arrangement of the parts, as hereinafter more fully set forth and 30 claimed, by which a more effective device of this character is produced than is now in ordinary use.

The nature and operation of the invention will be readily understood by all conversant 35 with such matters from the following explanation.

In the drawings, *A* represents the bed or body of the machine; *B*, the table, and *C* the main driving-shaft. The shaft is journaled 40 horizontally in the standards *D*, and carries the main gear *E*, pinion *F*, and driving-pulley *G*.

A crank-shaft, *H*, mounted in the standards *I*, has its crank *J* connected to the table *B* by the pitman *K*, jointed to the bracket or arm *L*, and carries a gear, *M*, which intermeshes with the pinion *F* on the shaft *C*.

The table *B* is pivoted at its rear end, *N*, to the hub *O*, projecting upwardly from the bed 50 *A*, and is provided at its forward end with two

small supporting-wheels, *P*, resting on the bed.

A shaft, *Q*, carrying the gear *R* and miter-gears *S S*, is mounted in proper bearings on the table *B* near its pivoted end *N*, and journaled horizontally at right angles to this shaft are two shafts, *T T*, respectively provided at their outer ends with miter-gears *U*, which intermesh with the gears *S* on the shaft *Q*. The inner ends of the shafts *T* work in vertically-sliding boxes (not shown) in the standards *V* on the table *B*, and respectively carry gears *W W*, the outer ends of the shafts *T* being so arranged in the boxes *a* as to permit the inner ends of the same to be raised and 65 lowered, as hereinafter described.

Arranged transversely on the table *B*, near its outer or free end, there is a head stock or bed, *X*, its upper side being in parallelism with the table *B*, and provided with a sliding 70 carriage, *Y*.

Journaled horizontally in the head-stock, beneath the carriage, there is a shaft, *Z*, carrying the gear *b*, which is connected with the gear *R* by the intermediate gears, *c d*, mounted in the standards *e f* on the table *B*. 75

Disposed in the lower part of the carriage *Y*, and journaled therein in parallelism with the shaft *Z*, there is a shaft, *g*, provided at its center with the gear *h*, and at one end with the gear *i*. The gear *h* intermeshes with the gear *b*, but does not traverse with the shaft *g* and carriage *Y*, being kept in position by the double flange or holder *j*, projecting from the bed *X*, and prevented from turning on said 85 shaft by the spline *k*.

Mounted horizontally in the upper part of the carriage *Y* there are two rollers, *l l*, journaled in suitable boxes, each of said rollers being provided with a gear, *m*, which intermeshes with the gear *i* on the shaft *g*. These 90 rollers are preferably arranged on the same plane in parallelism with each other and with the shafts *g Z*, and are constructed substantially alike, being smaller at the center than 95 at the ends, or gradually tapering from either end to the center, as shown in Figs. 3 and 4.

Pivoted to the short standards *n* on the table *B* there are two shipping-levers, *p p*, which project outwardly over the free end of 100

the table, as shown in Fig. 1, and have their inner ends respectively connected to the vertically-sliding boxes in which the inner ends of the shafts T rest.

5 A shipping-bar, q, is disposed on the outer end of the table B, being fitted to slide longitudinally in proper ways, 14, and provided with a downwardly-projecting stud, r, at either end, designed to engage with the fixed 10 stops t in the bed A. The bar is curved on its upper side or edge, being narrowest at the center and widest at the ends, as seen in Fig. 2, and the levers p project over it and have their outer ends connected by the rods 2 to a 15 horizontal lever, 3, (shown in the end view, Fig. 2,) the lever being pivoted at 4 on the front portion of the head-stock X.

Attached to the rear lower edge of the carriage Y there is a rack, 5, with which the gears 20 W' W are alternately engaged in moving the carriage back and forth on the head-stock X.

The cone or former 6, on which the sliver or felting material is deposited, is made in two sections, each section being provided with 25 a foot-piece, 7, and leg-piece 8, the leg-pieces being united on the line 9, and the feet or foot pieces turned in opposite directions, as best seen in Figs. 2 and 4, in order to balance the cone and enable it to be manipulated in a better manner. The taper of the leg-pieces of 30 the cone is designed to correspond with the taper of the rollers l, but in an opposite direction, the cone being largest at the center and the rollers smallest at that point, so that when 35 the cone is placed on the rollers, as shown in Fig. 3, it will be in perfect contact therewith the entire length of the rollers, or from the ankle-pieces 10 of the cone to the center 9, the cone being longer than the rollers, and 40 its feet projecting over the same, as shown in Fig. 2.

In the use of my improvement the machine is placed in a convenient position to receive the sliver of felt or felting material of which 45 the bat is to be formed from the card or other source of supply, the pivoted end N of the table being disposed nearest the end of the card, and the cone or former placed in position on the rollers, one end of the sliver of felt being 50 wound around the cone or passed over it downwardly between it and the outer roller l in such a manner as to be fed onto the cone properly when the machine is started up. The table B, being centrally arranged on the 55 bed A, as shown in Fig. 3, and the crank J nearly at its lowest point, power is now applied to the pulley G, causing the pulley and gear E to turn from the rollers l and said rollers to turn toward said gear or toward the 60 pivoted end of the table B, as shown by the arrows, thereby giving to the cone a rotary motion opposite that of the rollers, or in a direction opposite that in which the main gear E is revolving. The shaft H continuing to 65 revolve, the crank J will pass downwardly and cross a vertical line drawn through the center of said shaft, acting on the pitman K

as it rises to swing the table B to the left, or toward that side of the bed marked 27 in Fig. 2. The gear W', being at the same time engaged with the rack 5, and the gear W disengaged therefrom, the carriage Y will be caused to traverse or move on the head-stock X in the same direction with that in which the table B moves, but at a different rate of speed, 75 or will move toward the side 27 of the bed A, while the table is moving toward the same side. When the table has traversed far enough to bring one of the studs r into contact with the stop t which is on the side 27 of the bed A, 80 the shipping-bar q will be prevented from traversing any farther with the table in that direction, causing the shipping-lever p nearest the side 27 to ride upwardly on the curved end of the shipping-bar, lifting the outer end 85 of said shipping-lever and depressing its inner end, thereby, by means of the connecting-lever 3, disengaging the gear W' from the rack 5, and at the same time causing the gear W to become engaged therewith and the motion of the carriage Y to be reversed. When the crank J arrives on a plane with the axial line of the shaft H, or "passes the center" on its return, the movements of the table B will 90 also be reversed, and it will be caused to travel in the direction of the side 28 of the bed A until the crank passes said plane again on the opposite side of its shaft. As the table moves toward the side 28 the stud r in that end of the shipping bar q which is nearest 95 said side will strike its stop t, causing the shipping-bar to act on the shipping-lever p to bring the gear W' again into engagement with the rack 5 and disengage the gear W, thereby reversing the movements of the carriage Y in 100 a manner which will be readily obvious without a more explicit description.

The shipping-levers being connected to the pivoted lever 3 by the rods 2, it will be evident that when the bar q acts to raise one of 110 said levers the opposite or companion lever will be correspondingly depressed, the formation of the upper side or edge of said bar permitting this, as shown in Fig. 2.

The teeth of the gears E R are rounded, as 115 best seen in Fig. 4, to permit the table to be swung alternately to the right and left, as described, the pitman K being also loosely connected to the crank-pin of the crank J, for the 120 same reason.

The sliver of felting as it comes from the card passes in a direct line to the cone or former mounted on the rollers l l, and as the cone is moved back and forth under the sliver in the arc of a circle of which the pivoted end 125 N is the center, the sliver will be crossed and recrossed on the cone in such a manner as to greatly strengthen the fabric of the boot or other article being formed on the cone. It is, however, desirable, in order to perform the 130 work in the best manner, that all portions of the cone should receive the layers of the sliver properly or be held in the line of its delivery to the machine a proper time as it moves back

and forth under the same, which would not be accomplished if the rollers *l* were mounted directly on the head-stock *X*, for the reason that when the table, swinging either to the right or left, approaches the end of its course its speed is gradually decreased until it stops, or until the crank reaches its "dead-center," and when it starts to return its speed is gradually increased through the first part of its course, or until the crank reaches a point midway between its dead-centers, after which it will be again gradually decreased until it reaches the opposite end of its course, and vice versa. To obviate this difficulty, I make use of the carriage *Y*, traversing with the head-stock, but having independent or differential movements, as herein described, whereby the cone is kept moving under the sliver at a sufficient speed and for a sufficient distance in either direction to perform good work, even when the table *B* is nearly motionless or at rest, it being obvious that the speed of all the gears will be uniform, whereas in converting the rotary movements of the crank into the reciprocating movements of the table, the speed at which the table will move will vary in different parts of its course, as described.

The movements of the carriage being independent of the head-stock in so far as the same are derived from the gear *E*, rack 5, and the intermediate gears, it will continue to advance at its independent speed when the movements of the table are retarded as described, so that before the table stops at the end of its course the carriage, traveling in the same direction, will have passed beyond the table, or will have advanced so far as to project quite a distance over the end of the head-stock.

The shipping-bar *q* is preferably so constructed and the studs *r* and stops *t* so adjusted as to operate the shipping-levers and cause the movement of the carriage to be reversed immediately before the table stops at either end of its course; but the carriage may be arranged to stop coincidently with the table, and have its movement reversed at the same time or subsequently with that of the table, if preferred.

I do not confine myself strictly to the use of a cone or former having two feet or otherwise constructed as described, as a straight cone or cone of any other suitable shape may be used with the machine when the rollers are made to conform thereto. Neither do I confine myself to the respective devices shown for causing the table and carriage to traverse, or to any special means for revolving the cone, or to the respective devices shown for reversing the movements of the table or carriage, as these features may be changed materially without entirely departing from the spirit of my invention.

An annular groove is formed between the leg-sections 8 of the cone to serve as a guide to the shears in cutting open the bat at that point prior to removing it from the cone,

which may be readily accomplished when the cone is revolving on the rollers *l* by inserting the point of one blade of the shears through 70 the bat into the groove and severing the bat as it is revolved on the cone.

It will be understood that after a bat is formed on the cone as described it is to be removed, hardened, fulled, treed, and submitted to the 75 other necessary processes to produce a finished boot, shoe, or stocking, as the case may be.

The bed *A* may be independent of the floor of the room in which the machine is used, or the floor may be used in place of the bed, as 8c preferred.

The right is herein reserved to make a bat when formed as described, and also a felt boot, shoe, or stocking made from such a bat, the subject-matter of other Letters Patent, and 85 the same are not, therefore, claimed, broadly, in this specification, or when in and of themselves considered.

Having thus explained my invention, what I claim, is—

1. In a machine for making felt boots, shoes, or stockings, the table *B*, carrying the carriage *Y*, and rollers *l*, in combination with operative mechanism therefor, said carriage and rollers being adapted to move longitudinally 95 at a different speed from the table, substantially as and for the purpose set forth.

2. In a machine for making felt boots, shoes, or stockings, the rollers *l*, provided with the gears *m m*, the shaft *g*, having the spline *k*, and 100 provided with the gears *i h*, and the carriage *Y*, having the rack 5, in combination with the gears *W W'*, shaft *Z*, gear *b*, and operative mechanism, substantially as specified.

3. In a machine for making felt boots, shoes, or stockings, the shipping-bar *q*, provided with the studs *r r*, in combination with the stops *t*, 105 shipping-levers *p p*, gears *W W'*, rack 5, and operative mechanism, substantially as and for the purpose set forth.

4. In a machine for making felt boots, shoes, or stockings, the following instrumentalities, to wit: a cone or former for receiving the sliver or felting material from the card, a pair of rollers adapted to receive and support the cone and give it rotary movement, a carriage in which the rollers are mounted, and a table for supporting the carriage, in combination with operative mechanism by which the table, carriage, and rollers are moved 120 back and forth as the sliver is deposited on the cone, the longitudinal movement of the rollers not being in unison with the like movements of the table or support on which the carriage or the rollers is supported, substantially 125 as and for the purpose set forth.

5. In a machine for making felt boots, shoes, or stockings, a pair of rollers for supporting the cone on which the boot, shoe, or stocking is formed, said rollers being mounted 130 in a carriage or support, and moving longitudinally in the same direction with that of the table on which the carriage is supported, and at a rate of speed which is not uniform

with that of the table, substantially as described.

6. In a machine for making felt boots, shoes, or stockings, the shaft H, crank J, pitman K, gear M, shaft C, gears E F, shaft Q, gears S S, shafts T T, gears U U W W' d c, table B, and means for supporting and operating the rollers l l, substantially as set forth.

7. In a machine for making felt boots, shoes, or stockings, the cone 6 for receiving the sliver, said cone having the leg-pieces 8 joined at 9, and provided with feet 7, projecting in opposite directions, in combination with rollers for revolving said cone, substantially as specified.

8. In a machine for making felt boots, shoes, or stockings, the carriage Y, provided with the rack 5, the rollers l, provided with the gears m, and the shaft g, provided with the gear i, in combination with means for giving said carriage longitudinal reciprocating movements on the head-stock X, substantially as set forth.

9. In a machine for making felt boots, shoes, or stockings, the shafts T T, each provided with a gear adapted to engage the rack 5 at regular intervals, in combination with operative mechanism, substantially as specified.

10. In a machine for making felt boots, shoes, or stockings, the table B, pivoted at N, and provided with the head-stock X, carriage Y, and rollers l l, in combination with operative mechanism therefor, substantially as set forth.

11. In a machine for making felt boots, 35 shoes, or stockings, a cone or former for receiving the sliver or felting material from the card, in combination with means for supporting and revolving said cone, and means for giving it longitudinal reciprocating movements in the arc of a circle, substantially as specified.

12. A cone or former for felt boots, shoes, or stockings, having a groove, 9, to aid in cutting the bat, substantially as set forth.

13. In a machine for making felt boots, shoes, or stockings, the table B, pivoted at one end and provided at its opposite end with a supporting wheel or wheels, P, in combination with a cone on which the bat is formed, 50 means for supporting and revolving said cone, and means for producing reciprocating vibratory movements of the table in the arc of a circle, substantially as specified.

14. In a machine for making felt boots, 55 shoes, or stockings, a table pivoted to swing in the arc of a circle and so arranged that its pivoted end is nearest the card from which the sliver is taken, said table being provided with a carriage moving differentially thereon, 60 and carrying a cone or former, in combination with means for rotating the cone, causing the carriage to traverse and give the table movements, substantially as set forth.

LAURENT RUEL.
